UNITED STATES PATENT OFFICE

JOHN TAVIS, OF BAYSIDE, NEW YORK, ASSIGNOR TO MENDEL SINGER, SAMUEL SINGER, NATHANIEL SINGER AND HAYWARD SINGER, COPARTNERS TRADING AS M. SINGER & SONS, OF NEW YORK, N. Y.

DESIGN FOR AN UPHOLSTERED SOFA OR SIMILAR ARTICLE

Application filed February 8, 1933. Serial No. 47,149. Term of patent 3½ years.

To all whom it may concern:

Be it known that I, JOHN TAVIS, a subject of the Kingdom of England, and a resident of Bayside, Long Island, in the county of Queens, city and State of New York, have invented a new, original, and ornamental Design for an Upholstered Sofa or Similar Article, of which the following is a specification, reference being had to the accompanying drawing, forming part thereof.

The figure is a perspective view of an upholstered sofa, showing my new design.

I claim:

The ornamental design for an upholstered sofa or similar article, as shown.

JOHN TAVIS.
